[57] CLAIM

The ornamental design for golf stance training device, as shown and described.

DESCRIPTION

FIG. 1 is a top plan view showing our golf stance training device as deployed for use and showing our new design;

FIG. 2 is an end elevational view thereof, it being understood that the opposite end view appears as the mirror image thereof;

FIG. 3 is a left side elevational view thereof;

FIG. 4 is a right side elevational view thereof;

FIG. 5 is a bottom plan view thereof; and,

FIG. 6 is a perspective view thereof in folded position.

FIG-1
